GRINDING MACHINE

Bernardo D'Achille, New Kensington, Pa.

Application March 10, 1941, Serial No. 382,635

3 Claims. (Cl. 100—48)

The present invention relates to improvements in grinding machines and has particular reference to machines for grinding and crushing meat, fruits, vegetables and the like.

An object of the invention is the provision of a grinding machine of generally improved design.

Another object of the invention is to provide a grinding machine which is constructed so as to facilitate cleaning thereof.

A further object of the invention is the provision of a grinding machine composed of parts which may be quickly and easily separated or assembled.

Still another object of the invention is to provide a machine of the aforesaid character which is efficient in operation and durable in construction.

Other objects and advantages of the invention will become apparent as the description progresses.

In the accompanying drawing forming a part of this specification and in which like numerals are employed to designate corresponding parts throughout:

Figure 1 is a longitudinal sectional view through the assembled machine.

Figure 2 is a fragmentary detail elevation showing a modified connection, and

Figure 3 is a longitudinal section taken on line 3—3 of Figure 2.

Referring to the drawing, wherein is illustrated a preferred embodiment of the invention, 10 designates the body of a grinder casing which is of approximately cylindrical formation shaped at the top to provide an enlarged circular hopper 11. The body 10 is formed with a rearwardly directed stepped sleeve 12 having the bore thereof in axial alignment with a front opening 13.

To the hopper 11 is connected, as by the pin and bayonet slot connection 46, a funnel 47 for feeding the material to be ground into the grinder casing.

To the front of the grinder body 10 is detachably connected, in registration with the front opening 13, an elongated tubular extension section 48 held in position by a ring fitting 49 having an outwardly flaring lip 50. The extension section 48 in the form of a frusto-conical rigid perforated member disposed axially of the casing and having a diminishing taper toward its outer end. On the outer reduced end of the perforated section or sieve 48 is mounted an extension fitting in the form of an angular discharge spout 51 having its inner portion telescopically fitted over the open end of the sieve.

A tapered worm 51 is mounted to extend axially through the casing body and the extension sieve and is driven through the medium of a separable shaft section having a rearwardly directed circular portion 52 journaled in the sleeve 12 and a forward portion 53 arranged concentrically within a bore 54 of the worm. This shaft is provided with a thrust collar 55 bearing against the rear wall of the casing and a reduced squared extension 56 fitted in a correspondingly shaped socket in the worm to provide a driving connection. A compression spring 57 coiled about the shaft portion 53 tends to yieldingly thrust the worm forwardly in the sieve. This thrust movement is counteracted at the forward end by a coiled compression spring 58 mounted to extend axially between washers 59 and 60, the latter bearing against a pin 61 extending transversely through the rear portion of the spout 51. This spring mounting is designed to yieldingly position the worm so that the edge portion is arranged close to the sieve but not directly contacting the same.

The products to be ground or crushed and for the extraction of juice are fed through the funnel 47 onto the rear portion of the worm and, upon rotation of the latter, advanced through the sieve 48 wherein it is subjected to a grinding and crushing action which effectually squeezes the juice from the solid pulp matter. The extracted juice flows through the apertures in the sieve into a suitable receptacle, the flaring lip 50 serving to divert liquid flowing rearwardly down the sieve and preventing accumulation of juice on the body. The solid matter remaining in the sieve is forced through the forward end thereof and discharged through the spout 51 into a suitable collection receptacle.

I also contemplate a modified structure for the connection of the spout 51 with the outer reduced end of the sieve 48, as shown at Figures 2 and 3. In this arrangement a fastener ring 62 is welded or otherwise secured on the sieve inwardly of a cylindrical end portion 63 thereof, the edge indicated at 64 being formed with an angular flange 65 of enlarged diameter forming, in conjunction with the portion 63, an annular groove in which is to be fitted the companion portion of the spout and which portion is provided with bayonet slots 66 adapted to engage pins 67 projecting radially outward of the portion 63. This connection affords a tight leak-proof joint which is quickly and easily detachable for removal of the spout when necessary.

It is to be understood that the forms of my

invention herewith shown and described are to be taken as preferred and modified examples of the same and that various changes relative to the material, size, shape and arrangement of parts may be resorted to without departing from the spirit of the invention or the scope of the subjoined claims.

Having thus described my invention, I claim:

1. In a device of the character described, a body casing, an apertured tubular extension connected with and projecting from the casing, a worm rotatably journaled in the casing and extending through the tubular extension, a spring acting to yieldingly force the worm axially outward of the casing, and a second spring acting against the outer end of the worm yieldingly forcing the same inward of the casing.

2. In a device of the character described, a body casing, a perforated tubular extension connected to a side outlet of the casing and projecting therefrom, the said extension having a diminishing taper toward its outer end, a discharge spout attached to the outer end of the

5 said extension, a worm journaled in the casing and extending through the tubular extension, a spring acting against the inner end of the worm to yieldingly force the same outward of the casing, and a spring mounted in the discharge spout and acting against the outer end of the worm to yieldingly force the same axially inward of the casing.

10 3. In a device of the character described, a body casing having a discharge outlet, a perforated tapered extension removably connected to the outlet of the body and projecting therefrom, a rotary worm extending through the casing and the tapered extension, the said worm having that portion thereof within the extension tapered in correspondence with the taper of the extension, and means acting against the said worm so as to maintain the tapered portion in close proximity to and spaced from the tapered extension while allowing resilient axial displacement of the worm in both directions.

BERNARDO D'ACHILLE.
